ATTORNEY

UNITED STATES PATENT OFFICE

ALFRED H. JAHNS, OF SEATTLE, WASHINGTON

BATH CABINET

Application filed May 27, 1929. Serial No. 366,240.

The invention is a bath cabinet that is made of enameled metal plates having interlocking joints, and is so constructed that it can be shipped knocked down and readily set up in place without making permanent connections and without danger of leaking or seepage of water, as is prevalent in tile and concrete cabinets.

The object of the invention is to provide 10 a shower bath cabinet in which the walls cannot crack, or the joints leak.

Another object of the invention is to provide a metallic bath cabinet made with interlocking joints so that it can easily be shipped and readily set up, which will not leak.

Another object of the invention is to provide a shower bath cabinet that may be set up in sections instead of built up with tile, which will have as neat an appearance and 20 will last longer than tile.

A further object of the invention is to provide a bath cabinet that may be built complete in a plant, shipped in a knocked down condition, and readily set up in place.

25 A still further object of the invention is to provide an enameled metal shower bath cabinet that may readily be built into a structure.

And a still further object of the invention 30 is to provide means for constructing a shower bath cabinet which is of a simple and economical construction.

With these ends in view the invention embodies a base having a drain opening in the 35 center, and upwardly extending flanges at the sides, a plate forming a back having flanges at the sides, an over-lapping flange at the lower edge, and a channel shaped flange at the upper edge, side plates with inwardly extending flanges at the front, 40 over-lapping flanges at the lower and rear edges, and channel shaped flanges at the upper edges, and a channel shaped member extending across the top at the front.

Other features and advantages of the invention will appear from the following description taken in connection with the drawings, wherein:

50 Figure 1 is a view showing a front ele-

vation of one side of the cabinet with the other side broken away on the center line.

Figure 2 is a cross section through the central portion of the cabinet taken at right angles to the view shown in Figure 1.

Figure 3 is a sectional plan taken at any point through the central portion of the cabinet.

Figure 4 is a view showing the cabinet as it would appear installed ready for use with a corner thereof broken away to show the framing in connection therewith.

In the drawings the device is shown as it would be made wherein numeral 1 indicates a pan forming the base, numeral 2 the back, 65 and numeral 3 the side members.

The pan 1 may be made as shown with a flat plate sloping downward toward the center and with a drain opening 4 in the center. The edges are bent upward forming a continuous flange 5, as shown, and it will be observed that the upper plates 2 and 3 extend downward inside of the flange. The rear plate 2 is made as shown with the lower edge bent upward and then over and 70 downward forming a lap joint that may be placed over the flange 5 as shown at the point 6 in Figure 2. The edges of the plate 2 are bent forward forming flanges 7, as shown in Figure 3, and the top of the plate is bent inward from the point 8 to the point 9, then upward to the point 10 and then outward to the point 11 thereby forming a channel shaped section.

The side plates 3 are formed with inwardly extending flanges 12 at the front, lap joints 13 at the rear in which the flanges 7 on the rear plate 2 are held, and channel shaped sections as indicated by the numeral 14, at the upper edge. These plates are also 85 provided with lap joints as indicated by the numeral 15 at their lowest edges, which fit over the flange 5. The channel shaped sections at the top are filled in with wood or a suitable filler, as indicated by the numeral 16, and are provided with bolt holes 17 so that the upper end of the cabinet may be bolted through the filler to studding or other framework, which is indicated by the numeral 18 as shown in Figure 4. It will be 100

understood that although studding is shown and described the cabinet may be used in combination with any other type of frame work or building material. The space between the studding or frame work and the outside of the plates may be filled with plaster or the like as indicated by the numeral 19. A channel shaped member 20 is provided at the front of the cabinet to form a closure for the upper end and this is also provided with bolt holes and may also be filled in with a wood beam or other material, as shown in Figure 4.

The exposed surfaces of the plates may be chemically treated and coated with vitreous enamel which is the same as the enamel used on tile, so that it will therefore, have a somewhat similar appearance except that the joints between the tile will be eliminated. This enamel may have any suitable color or tint or any suitable combination of colors may be used, and it may be applied and baked in a plant, or painted on the plates after they are in place, or any suitable paint may be used.

It will be understood that changes may be made in the construction without departing from the spirit of the invention. One of which changes may be in the use of any other combination of plates, another may be in the use of joints of any other type for sealing the edges, and another may be in the use of any other means for holding the plates.

The construction will be readily understood from the foregoing description. In use the plates may be formed and enameled at the factory, shipped independently or knocked down and readily installed by placing the lap joints over the flanges as hereinbefore described and connecting the upper end to the frame work. The plumbing fixtures may be installed at any suitable point and openings may be provided through the plates for the spray and valve fittings. In the arrangement shown in Figure 4 the valve fittings extend through one side of the cabinet as shown at the point 21 and a pipe 22 may extend from this point up over the cabinet and down to a spray 23 in the center thereof. It will be understood, however, that these fittings may be located as shown in Figure 1, or at any suitable point and any suitable type of fittings may be used. The arrangement of the cabinet shown in Figure 4 may be considered typical as the cabinet is built in with the door opening in the wall similar to the opening formed between the flanges 12 with the lower edge of the member 20 at the top and the upper edge of the flange 5 as the floor line. It will be appreciated, however, that several cabinets may be installed in combination and also that any other arrangement may be used.

Having thus fully described the inven-

tion, what I claim as new and desire to secure by Letters Patent, is:

1. In a shower bath cabinet of the character described, a pan with a continuous flange extending upward at the edges and the bottom sloping downward to a drain opening in the center forming a base, upwardly extending plates with their lower edges fitting inside of the flange of the base, lap joints at the lower edges of the plates fitting over the flange of the base, other lap joints at the sides of the plates fitting over flanges at the sides of adjoining plates forming sealed joints at the corners, a door opening in one of the sides, and channel shaped sections indented at the upper edges of the plates for reenforcing the same and through which the plates may be held to adjoining frame work.

2. In a shower bath cabinet of the character described, a rectangular shaped pan with the bottom sloping downward to a drain opening at the center, and flanges extending upward at the sides, plates forming sides and a back with their lower edges fitting inside of the flanges of the base, lap joints between the plates and between the plates and flanges of the base, inwardly extending flanges at the forward edges of the side plates and means at the upper ends of the plates by which they may be held.

3. In a shower bath cabinet of the character described, a rectangular shaped pan with the bottom sloping downward to a drain opening, and flanges extending upward at the sides, plates forming sides and a back with their lower edges cooperating with the flanges of the base, joints between the plates and between the plates and the flanges of the base, inwardly extending flanges at the forward edges of the side plates and means at the upper ends of the plates by which they may be held.

In testimony whereof he affixes as his signature.

ALFRED H. JAHNS.
